(57) **CLAIM**

The ornamental design for a game controller, as shown and described.

DESCRIPTION

FIG. 1 is a perspective view of a game controller embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is front perspective view, showing the claimed design in an extended position;

FIG. 9 is a rear perspective view, thereof; and,

FIG. 10 is an enlarged view of the selected portion 10 in FIG. 1.

The broken lines in the drawings depict portions of the game controller that form no part of the claimed design. The circular broken lines and indicia, in FIGS. 1 and 10, illustrate bounds of the magnified portions and form no part of the claimed design.
